UNITED STATES PATENT OFFICE.

ARTHUR L. CHURCH, OF PHILADELPHIA, PENNSYLVANIA.

VALVE FOR COMPOUND ENGINES.

SPECIFICATION forming part of Letters Patent No. 471,842, dated March 29, 1892.

Application filed November 26, 1889. Serial No. 331,630. (No model.)

To all whom it may concern:

Be it known that I, ARTHUR L. CHURCH, a citizen of the United States, and a resident of Philadelphia, Pennsylvania, have invented 5 certain Improvements in Valves for Compound Engines, of which the following is a specification.

The object of my invention is to construct a valve especially adapted for use in connection with tandem compound engines, my invention being especially applicable for use with compound locomotive-engines; but it can also be applied to stationary and marine engines.

15 In the accompanying drawings, Figure 1 is a longitudinal section of the high and low pressure cylinders and valve, the valve being shown on dead-center. Fig. 2 is a section view showing the valve moved to admit steam in the rear of the pistons. Fig. 3 is a view showing the valve moved to admit steam in front of the pistons.

A is the high-pressure cylinder, and B the low-pressure cylinder, arranged in line with 20 each other. The piston-rod D passes from one cylinder to the other and carries the pistons a and b.

E is the valve-chest, and F is the valve, and is what is termed a "piston-valve."

25 e e' are the steam-inlet ports, and C the exhaust-port. d d' communicate with the opposite ends of the high-pressure cylinder, and the ports g g' connect with the opposite ends of the low-pressure cylinder. The valve F

30 has an internal passage f and has a series of annular grooves i, i', and i''. The groove i communicates with the internal passage f through the openings j. The groove i' forms a communication at times between the steam-inlet port e' and the port d' of the high-pressure cylinder, and the groove i'' forms a communication between the ports of the low-pressure cylinder and the exhaust, but does not communicate with the internal passage.

45 Passages j' and j'' form inlet communications with the ports g g' of the low-pressure cylinder from the central passage f of the valve, the valve F being closed at both ends, as shown in the drawings. It will be noticed

50 that the steam-inlet ports are in one half of the valve-casing, as are also the high-pressure ports, while the low-pressure ports and the exhaust-ports are in the opposite half of the valve-casing, so that by arranging the cylinders in tandem, as shown, direct commu-

nication will be had between the valve and either cylinder. The construction of the cylinders themselves may vary. They may be placed near together or far apart or out of line, depending altogether upon the particular construction of engine to which my improved valve applies. If the valve is moved from the position shown in Fig. 1 in the direction of the arrow to the position shown in Fig. 2, steam will be admitted to the high-pressure cylinder through the ports d and e and the steam will exhaust from the high-pressure cylinder into the low-pressure cylinder through the port d', the space i, and passage j to the central passage f of the valve 60 through the passage j' to the port g of the low-pressure cylinder to the rear of the piston. The steam exhausts from this cylinder through the passage g' and space i'' to the exhaust C. The pistons will consequently move 65 forward. If the valve is moved to the position shown in Fig. 3, steam will be admitted through the steam-inlet port e' and port d' of the high-pressure cylinder in front of its piston, while the exhaust-steam from this cylinder will pass to the low-pressure cylinder through the port d, space i, passage j, central passage f in the valve, and passage j'' through the port g' to the low-pressure cylinder in front of its piston, and steam will exhaust 75 from this cylinder through the port g and space i''.

I claim as my invention—

The combination, in a valve structure for compound engines, of the valve-chest having 80 at one end two live-steam-admission ports e e' and two inlet and exhaust ports d d' for the high-pressure cylinder situated between the two live-steam-admission ports and having at the opposite end an exhaust-port C and two inlet and exhaust ports g g' for the low-pressure cylinder, one on each side of the exhaust-port C, with a hollow valve F, closed at each end, forming a passage f and having grooves i i', and openings j j'' in the valve for 85 the passage of steam from the high-pressure cylinder to the low-pressure cylinder, substantially as described.

In testimony whereof I have signed my name to this specification in the presence of 105 two subscribing witnesses.

ARTHUR L. CHURCH.
